(57) **CLAIM**

The ornamental design for a sanitization cabinet, as shown and described.

DESCRIPTION

FIG. 1 is a top front and right side perspective view of a sanitization cabinet, showing our new design;

FIG. 2 is a top front and left perspective view thereof;

FIG. 3 is a front elevation view thereof;

FIG. 4 is a back elevation view thereof;

FIG. 5 is a left side elevation view thereof;

FIG. 6 is a right side elevation view thereof;

FIG. 7 is a top plan view thereof; and,

FIG. 8 is a bottom plan view thereof.

The broken lines immediately adjacent the shaded areas represent the bounds of the claimed design, while all other broken lines are directed to environment and are for illustrative purposes only; the broken lines form no part of the claimed design.
